Patented Apr. 20, 1915.

UNITED STATES PATENT OFFICE.

NATHANIEL D. MERTZ, OF FREEPORT, ILLINOIS.

HALTER.

1,136,693.

Specification of Letters Patent. Patented Apr. 20, 1915.

Application filed March 30, 1914. Serial No. 828,217.

To all whom it may concern:

Be it known that I, NATHANIEL D. MERTZ, a citizen of the United States, residing at Freeport, in the county of Stephenson and State of Illinois, have invented certain new and useful Improvements in Halters; and I do hereby declare the following to be a full, clear, and exact description of the invention, such as will enable those skilled in the art to 10 which it appertains to make and use the same.

My invention relates to halters and consists in the peculiar construction and connection of certain parts whereby I obtain a halter of a superior class as will be hereinafter more fully described and set forth in the claims hereto annexed.

In the accompanying drawings, which will illustrate a halter embodying my invention 20 and form a part of this specification, Figure 1 is a side elevation, Fig. 2 a front elevation, Fig. 3 a top plan view, and Fig. 4 a detailed perspective showing the manner in which the brow-band is slidably adjustable through 25 the ends of the crown-piece.

Referring to the drawings by letter, the same letter indicates corresponding and like parts in all the figures.

Letter A designates the cheek-pieces, B 30 the crown-piece, C the jaw-pieces, D the nose-piece. The cheek-pieces A are preferably connected with the nose-piece D and the jaw-pieces C by the loop G. The crown-piece B is preferably connected with the 35 cheek-pieces A by the loop H.

a' designates a metal buckle by which the cheek-pieces A may be adjusted.

b' is a short piece of leather to which is fastened the metal buckle b'' by which the 40 crown-piece B may be adjusted. Where the crown-piece B connects with the loop H an opening c' is made in which is slidably mounted the brow-band F.

d' is a metal ring which connects the jaw- 45 pieces C.

F designates the brow-band which consists of a single piece of rope, the opposite ends of which pass through the openings c' on opposite ends of the crown-piece, thence 50 through the metal ring J, which ring J adjusts the brow-band in such a manner as to form a throat-latch. After passing through the ring J the brow-band F continues on through the metal ring d', which connects 55 the jaw-pieces C, and is then permanently attached to the ring I by intertwining the

ends of the rope. To this ring I the hitching strap K is attached.

The foregoing construction forms a simple and cheap halter, with nose-piece, crown-piece, brow-band, cheek-pieces, and throat-latch, and it will be obvious that owing to the brow-band being slidably mounted in the ends of the crown piece that the slightest pull on the hitching strap will tighten 60 the brow-band, and the brow-band only. 65

What I claim as new, and desire to secure by Letters Patent, is set forth fully in the following claims:

1. A halter including a nose piece, cheek 70 pieces, a crown piece, a brow band, and a hitching strap connected to the brow band so constructed and arranged that a pull upon the strap will tighten the brow band about the brow of the animal. 75

2. A halter including a nose piece, cheek pieces, a crown piece, a brow band arranged for movement relative to and transversely of said crown piece, and a hitching strap so connected with the brow band that a pull 80 upon the strap will tighten the brow band about the head of the animal.

3. A halter provided with a nose piece, cheek pieces, a crown piece, and a slidably mounted brow band. 85

4. A halter provided with a nose piece, cheek pieces, a crown piece and a brow band slidably mounted in said crown piece.

5. In a halter a brow band, a nose-piece, jaw-pieces, cheek-pieces fastened to said 90 nose-piece and jaw-pieces, and having their upper extremities fastened to a crown-piece, means being provided at the ends of the crown-piece by which the brow-band is slidably mounted, a throat-latch, means for adjusting the cheek and crown pieces, and a hitching strap so connected with the brow band that a pull upon the strap will tighten 95 the brow band about the brow of the animal.

6. In a halter a brow band, a nose-piece, cheek-pieces and jaw-pieces, said nose-piece and jaw-pieces being fastened together so as to form a continuous piece, the cheek-pieces being fastened to the nose-piece and jaw-pieces, the cheek-pieces also being fastened at their upper extremities to a crown-piece, the said crown-piece being provided at the point of connection of the cheek-pieces and crown-piece with means for slidably mounting the brow-band, a throat-latch, 105 means for adjusting the cheek and crown pieces, and a hitching strap so connected 110

with the brow band that a pull upon the strap will tighten the brow band about the brow of the animal.

7. In a halter the combination of a brow band, a nose-piece, jaw-pieces fastened to the nose-piece, cheek-pieces fastened to the nose and jaw pieces at the point of connection of the nose-piece and jaw-pieces, the cheek-pieces also being connected at their upper extremities to a crown-piece, the ends of said crown-piece being returned upon itself to form loops in which the brow-band is slidably mounted, means for adjusting the cheek and crown pieces, and a hitching strap so connected with the brow band that a pull upon the strap will tighten the brow band about the head of the animal.

8. In a halter a nose piece, jaw-pieces connected to said nose-piece and connected at their extremities by a metal ring, cheek-pieces fastened to said nose-piece and jaw-

pieces, the said cheek-pieces being fastened at their upper extremities to a crown-piece, the ends of the crown-piece being returned upon itself so as to form loops, a brow-band slidably mounted in said loops so as to tighten, when the hitching strap is pulled upon, the ends of said brow-band after passing through said loop, then passing through a ring slideable upon the ends of the brow-band to form a throat-latch, thence through the ring connecting the ends of the jaw-pieces, the ends of the brow-band then being connected by a ring to which a hitching strap is fastened and means for adjusting the cheek and crown-pieces.

In testimony whereof I affix my signature in presence of two witnesses.

NATHANIEL D. MERTZ.
